UNITED STATES PATENT OFFICE.

ALONZO E. RHOADES, OF HOPEDALE, MASSACHUSETTS, ASSIGNOR TO DRAPER COMPANY,
OF HOPEDALE, MASSACHUSETTS, A CORPORATION OF MAINE.

BOBBIN-HOLDER.

No. 884,759.

Specification of Letters Patent.

Patented April 14, 1908.

Application filed October 19, 1907. Serial No. 398,251.

To all whom it may concern:

Be it known that I, ALONZO E. RHOADES, a citizen of the United States, and resident of Hopedale, county of Worcester, State of 5 Massachusetts, have invented an Improvement in Bobbin-Holders, of which the following description, in connection with the accompanying drawing, is a specification, like letters on the drawing representing like 10 parts.

This invention has for its object the production of a bobbin-holder for supporting a bobbin during the unwinding of the yarn therefrom, the construction and arrangement being such that the yarn may be delivered in two different ways according to the desired tension, means being provided whereby one of such ways of delivery can be rendered inoperative when desired. 15

20 I have also so constructed the bobbin-holder that the spent or empty bobbin may be ejected or discharged without handling by the attendant.

The various novel features of my invention will be fully described in the subjoined specification and particularly pointed out in the following claims. 25

Figure 1 is a side elevation of a bobbin-holder embodying one form of my present 30 invention; Fig. 2 is a top plan view thereof; Fig. 3 is a front elevation of the bobbin-holder, with a bobbin shown supported thereby.

Referring to Fig. 1, the bracket *b* having 35 attached thereto the rest or pan *d* on which the bobbin *C* is laid, the upturned arm *A* forming a part of the bracket, and the forked clamp *A'* provided with a set-screw *a*, may be and are of substantially well known construction, the clamp *A'* retaining the bobbin-holder on the supporting-bar *B* of the spooler. 40

The upper end *A* of the arm *A* is shaped to present a transverse shelf *a'* and an up-right shoulder *a''*, Fig. 1, and a headed stud *a* is fixed in the part *A* extended longitudinally above and parallel to the rest *d* but at one side, as shown clearly in Figs. 2 and 3. Upon this stud I mount an overhead, tilting 45 carrier *1* extended above the rest *d*, the rear end of said carrier being shaped to present a transverse seat *2*, Fig. 2, upon which is clamped the lateral head *3* of an elongated, depending side guard *4*, a screw-bolt *5* rigidly 50 securing the head and the carrier together. The head *3* has a hole formed therein to re-

ceive the fulcrum stud *a*, which is thus at one side of the carrier *1* but upon which the carrier may be tilted laterally, for a purpose to be described. As shown the side guard 4 is preferably a flat piece of metal, outwardly curved or flared at its front end at *6*, and longitudinally recessed at its lower edge at *7*, Fig. 1, to form a yarn guide when the yarn leading from the bobbin is delivered beneath and up outside of the guard, such delivery being adopted when it is desired to impart some tension or drag upon the yarn as it is led from the bobbin. 60 65

Referring to Figs. 1 and 3 it will be seen 70 that the upper edge of the guard *4* is slightly below the bottom of the carrier *1*, and in Fig. 3 it is plain that the guard is laterally offset from the carrier, leaving an elongated clearance or passage through which the yarn 75 may be led directly from the bobbin upward, to be delivered, and in such case there will be no extraneous drag or tension imposed upon the yarn, as will be obvious. Such delivery is employed when the yarn is fine or when 80 the pull thereon affords sufficient tension, the length of the clearance affording the proper traverse as the yarn unwinds from one to the other end of the bobbin.

Inasmuch as it is desirable to govern the 85 spooler tender as to the manner in which the yarn is to be delivered I have provided means to cross or obstruct the clearance when the yarn is to be delivered through the yarn-guide *7*. To this end I mount upon the 90 top of the carrier *1* a block *8* having extended therefrom a finger *9* of sufficient length to cross the clearance or passage when the finger is turned into dotted line position, Figs. 2 and 3, a set-screw *10* holding the 95 block in place and also clamping it in desired position.

The overseer will set the finger, and when it is in dotted line position the yarn cannot be delivered through the passage or clearance, 100 for said finger will obstruct the traverse of the yarn and break it, so that the attendant will not fail to effect the delivery by means of the yarn-guide *7*.

At the side of the carrier opposite the fixed 105 guard *4* I mount a depending, swinging side guard *11*, preferably made of wire and substantially of usual construction, the upper ends *12* of said guard being fulcrumed in suitable bearings in the carrier.

When a spent or empty bobbin is to be discharged or ejected from the bobbin-holder 110

the attendant grasps an upturned lug 13 on the carrier and tilts the latter on the stud a^3 , swinging the fixed guard 4 to the left, Fig. 3, across the rest d , and bringing said guard 5 into engagement with the bobbin.

The bobbin is pushed off the left hand side of the rest and discharged from the holder without handling by the attendant, the weight of the carrier and the parts connected thereto returning it to normal position when the lug 13 is released, the shelf a' limiting the return movement of the carrier and maintaining it in its normal, operative position.

The shoulder a^2 backs up or supports the rear end of the carrier and the adjacent face of the head 3 of the fixed guard 4, as will be evident from an inspection of Fig. 1.

Changes in details of construction may be made by those skilled in the art without departing from the spirit and scope of my invention as set forth in the claims appended hereto.

Having fully described my invention, what I claim as new and desire to secure by Letters Patent is:—

1. A bobbin-holder having a rest for the bobbin, a carrier mounted above the rest, a side guard for the bobbin pivotally mounted on and depending from the carrier at one side thereof, and a side guard fixedly mounted on the carrier at its opposite side and having its lower edge recessed to form a yarn guide.

2. A bobbin-holder having a rest for the bobbin, a carrier extended longitudinally above the rest, side guards for the bobbin, depending from the carrier, one of said guards being pivotally connected therewith and the other guard being rigidly connected with and laterally offset from the carrier, to leave a clearance through which the yarn may be led from the bobbin, a yarn-guide at the lower edge of the fixed guard, and a device on the carrier to cross the clearance when the yarn is governed by the yarn-guide.

3. A bobbin-holder having a rest for the bobbin, a carrier extended longitudinally above the rest, side guards for the bobbin, fixedly and pivotally connected, respectively, with the carrier, the fixedly connected guard being laterally offset to leave a yarn delivery passage, and means to cross said passage when the yarn is led from the bobbin around the lower edge of the fixed guard.

4. A bobbin-holder having a rest for the bobbin, a carrier extended longitudinally above the rest, a pivotally mounted side guard depending from the carrier at one side, a fixed guard at the opposite side, rigidly connected at its rear end with the carrier to

leave a longitudinal clearance through which the yarn may be delivered, a yarn guide at the lower edge of the fixed guard, and a manually adjustable finger on the carrier adapted to be positioned across the clearance, to prevent delivery of the yarn therethrough. 60 65

5. A bobbin-holder having a rest for the bobbin, a carrier fulcrumed above the rest to tilt on an axis parallel thereto, depending side guards pivotally and fixedly connected, respectively, with the carrier, the fixed guard being offset laterally to leave a clearance for delivery of the yarn, and means to cross the clearance when the yarn is to be delivered under the fixed guard, tilting of the carrier effecting ejection of the spent bobbin by 70 75 the fixed guard.

6. A bobbin-holder having a rest for the bobbin, a carrier fulcrumed above the rest to tilt on an axis parallel thereto, depending side guards pivotally and fixedly connected, respectively, with the carrier, the fixed guard being connected at its rear end only with the carrier, to permit delivery of yarn between said guard and the carrier, the lower edge of the fixed guard being recessed longitudinally 80 85 to form a guide for delivery of yarn around said guard, and a manually adjustable finger on the carrier to cross the space between the carrier and fixed guard and prevent delivery of yarn therethrough, tilting of the carrier 90 effecting ejection of the spent bobbin by the fixed guard.

7. A bobbin-holder having a rest for the bobbin, an overhead carrier, side guards for the bobbin, connected with the carrier to leave a longitudinal yarn delivery opening between the carrier and one of the guards, a yarn-guide at the lower edge of said guard, and means to at will prevent delivery of the yarn through said longitudinal opening. 100

8. A bobbin-holder having a rest for the bobbin, an overhead carrier adapted to be tilted laterally, a swinging side guard and a fixed side guard, mounted on the carrier to leave a yarn delivery opening between it and the fixed guard, and a device on the carrier manually movable into position to cross and prevent delivery of yarn through such opening, tilting of the carrier acting through a guard to eject a spent bobbin from the rest. 105 110

In testimony whereof, I have signed my name to this specification, in the presence of two subscribing witnesses.
